UNITED STATES PATENT OFFICE.

THEODORE W. FOSTER, OF PROVIDENCE, RHODE ISLAND.

DESIGN FOR A BOWL FOR TEA-SETS, &c.

SPECIFICATION forming part of Design No. 31,344, dated August 8, 1899.

Application filed July 8, 1899. Serial No. 723,251. Term of patent 7 years.

To all whom it may concern:

Be it known that I, THEODORE W. FOSTER, of Providence, in the county of Providence and State of Rhode Island, have invented and 5 produced a new and original Design for the Bowl of Tea-Sets or Similar Articles, of which the following is a specification, reference being had to the accompanying drawings, forming part thereof.

10 Figure 1 is a side view of a sugar-bowl, showing my design. Fig. 2 is a top view of the same.

Tea-sets usually consist of a number of pots, bowls, and cups, some with and some without handles and some provided with a 15 spout. In such sets the bowls of the several articles in a set are usually of the same shape and have the same ornamentation.

The leading feature of my design consists in the eight sides, two of which—one on each 20 side of the bowl—are broader than the rest, all having curved ogee surfaces, a wreath ornamentation on the broader, and festoons on the smaller of the sides or facets of the bowl, presenting to the eye an elongated eight-sided ogee bowl with a more distinctly ornamented central surface.

In the drawings, the base 1 slopes inward from the peripheral rim and curves upward to form the contracted stem, surrounded by 25 the pearl-beaded ring 2, from which the stem curves outward to join the convex bottom 3 of the bowl. The margin of the bottom 3 is eight-sided, as shown in Fig. 2. The four sides *a a* are of equal width. The sides or

facets *b b* are of greater width than the sides 35 *a a*, and the sides *c c* are of less width than the sides *a a*. This proportion is maintained in the bowl, in which the eight sides extend from the bottom 3 on outwardly-expanding ogee curves. The edge of the bottom of the 40 bowl is ornamented by the pearl-beaded border 4. Around the upper end of the bowl the pearl-beaded border 5 divides the bowl proper from the curved rim 6, having extended ewer-shaped margins at the opposite ends. On the 45 sides *b b* is a raised ornamentation consisting of the beaded central band 7, from which the foliated scrolls 8 extend in opposite directions to the pendent floral garland 9, covering the greater portion of the side or facet of 50 the bowl. The pendent floral garlands 10 ornament the upper part of the sides or facets *a a* of the bowl.

When handles or a spout are used on the bowls, these are secured on the sides or facets 55 *c c* of the bowl.

Having thus described my invention, what I claim as new, and desire to secure by Letters Patent, is—

The design for the bowl of tea-sets or similar articles herein shown and described.

In witness whereof I have hereunto set my hand.

THEODORE W. FOSTER.
